(57) **CLAIM**

The ornamental design for a seat cover, as shown and described.

DESCRIPTION

FIG. 1 is a front side perspective view of a seat cover positioned on a seat showing our new design;

FIG. 2 is a front view of a seat cover showing our new design;

FIG. 3 is a front view of a seat cover showing our new design;

FIG. 4 is a top plan view thereof;

FIG. 5 is a bottom plan view thereof;

FIG. 6 is a left side elevation view thereof;

FIG. 7 is a right side elevation view thereof;

FIG. 8 is a front side perspective view of a seat cover showing our new design positioned above a seat; and,

FIG. 9 is a front view of a seat cover showing our new design.

The broken lines in the figures are for the purpose of illustrating portions of the seat cover, which form no part of the claimed design. The additional broken lines in FIGS. 1, 5, 7 and 9 depicting a chair are to show environment and form no part of the claimed design.

1 Claim, 6 Drawing Sheets
